TEXTILE MFG. CO., INC., OF NEW YORK, N. Y.

FABRIC FOR CURTAINS

Application filed July 9, 1930. Serial No. 466,813.

This invention relates to new and useful improvements in the manufacture of printed or woven fabrics in the piece and more particularly to such fabrics adapted for use in the construction of window curtains made in the homes.

The primary object of the invention is to provide a fabric which has printed or woven therein a definite outline indicating where the fabric is to be cut to enable the party using 10 the material to produce a pair of curtains from the piece.

A further object of the invention resides in the printing or weaving into the fabric at 15 definite points thereon a border or trimming so that the hemming of the fabric after it is cut, is all that is necessary in order to complete a pair of curtains from a piece of this fabric.

The usual procedure in the manufacture of 20 a pair of curtains in the home is that material is purchased and cutting of the material is conducted in a more or less haphazard way, whereupon it is hemmed and an extra trimming of one kind or another is used to 25 complete the pair of curtains. This usual plan embodies several processes for cutting and sewing.

I have improved upon this usual method 30 of making curtains in the home by the adoption of a cutting line which is printed or woven into the fabric at a definite point therein and this eliminates entirely any guess work of the ultimate consumer of the fabric in cutting the curtains perfectly straight. The party cutting the fabric follows the line 35 definitely and it is impossible to cut crookedly, if this line is followed. This saves considerable time and eliminates the possibility of cutting incorrectly. Further my plan involves the printing or weaving into the fabric at the ends thereof and at a central point on 40 each side of the cutting line of a border or trimming which may be folded or hemmed and stitched, following the cutting.

My idea simplifies the method of making a 45 pair of curtains by requiring but two simple and minor operations. First the party cuts on the line and then hems the cloth from the cut end and from the opposite end over the

printed end or woven end border or trimming and the article is then complete. There is no further cutting or sewing necessary to produce a complete pair of curtains and the elimination of extra trimming is produced through this printed end or woven end border or trimming.

With these and other objects in view, my invention consists in the novel features of construction, combination and arrangement of parts which will be hereinafter referred to and more particularly pointed out in the specification and claims.

In the accompanying drawings, forming a part of this application:

Figure 1 is a plan view of a piece of the fabric, with parts broken away, showing the cut through the median line thereof;

Figure 2 is a fragmentary enlarged view thereof illustrating how the cut edge is folded or hemmed over the border or trimming;

Figure 3 is a diagrammatic sectional view showing the place where the fabric is cut and the place where it is folded;

Figure 4 is a similar view showing the fabric cut and folded, and

Figure 5 is a view similar to Figure 2 showing the obverse side of the fabric with dotted lines to indicate the fold.

In describing the invention I shall refer to the drawings in which similar reference characters designate corresponding parts throughout the several views and in which 1 indicates a sheet of fabric, preferably woven a definite width, such as 36 inches and having a definite motif woven therein. While it is preferable to refer to this fabric as being woven and having a motif woven therein, it will be understood that the fabric may be woven and a design or motif printed thereon.

The motif woven into the fabric is a checkered design, the checks or squares being of contrasting colors and at the ends of this sheet of fabric a border 2 of a darkened hue is woven therein. In this particular instance, the border 2 is of a width equivalent to six of the checks or squares in the body of the fabric and the border is adapted to be folded over along a line designated by the numeral 109.

3 to produce a hem and when so hemmed the fabric obviously is provided with a border trimming.

There is woven into this fabric 1 centrally thereof a line 4 which designates where the fabric is to be cut along the median line thereof in order to produce a pair of curtains. On each side of this line, the fabric is also woven with a panel 5 of darkened hue similar to the border or panel 2. This line 4 enables the material to be cut definitely and accurately in order to produce a pair of curtains. After being cut the material along the cut edge is adapted to be folded over the panel 5 along the line indicated in the drawings as 6. This over-fold or hem is similar to the hem provided at the outer marginal edges of the fabric and is equivalent, in this instance, to the width of two of the checks or squares in the body of the fabric. This fold or hem is clearly shown in Figure 2 of the drawings and also in Figure 4 which is a diagrammatic view. The fold or hem is designated by the numeral 7. When folded the hem is stitched, the same as the fold at the marginal ends of the fabric and in this manner a pair of curtains is provided from a sheet of this fabric and each of the curtains is provided with a "woven end" border or trimming. No additional trimming becomes necessary. In Figure 5 there is shown the obverse side of the fabric from that illustrated in Figure 2 and it will be seen that the panel or border or trimming 5 is of a solid hue on its one side which faces outwardly and thus a curtain is provided in which a motif is embodied in the body of the fabric and a trimming, border or panel provided at the marginal edges of the cut, contrasting in color with that of the body of the fabric but requiring no additions thereto as a trimming for the curtains. It should be noted that the face of the trimming shown in Figures 1 and 2 is formed with horizontal stripes whereas the face shown in Figure 5 is of a solid color except the portion between the fold line 6 and cutting line 4 which is striped the same as the face shown in Figure 2. Therefore, when the trimming is folded along the line 6 the striped face of the folded portion forming the hem will blend with the striped face it overlaps and the curtain will be neat in appearance when viewed from either side. The trimming along the sides of the strip of fabric are similarly woven. Through the medium of my improved fabric, it will be seen that I have provided a means for economically producing a pair of window curtains, since but two simple operations are necessary in order to produce the same, to wit, the cutting of the sheet of fabric along a definite line and the hemming of the cut portions to produce the border or trimming therefor.

From the foregoing description of the construction of my invention, the manner of pro-

ducing the curtains will be readily understood and it will be seen that I have provided a simple, inexpensive and efficient means for carrying out the objects of the invention.

While I have particularly described the elements best adapted to perform the functions set forth, it is apparent that various changes in form, proportion and in the minor details of construction may be resorted to without departing from the spirit or sacrificing any of the principles of the invention.

What I claim is:

1. In an article of manufacture, a sheet of fabric having a motif woven therein and having panels of darkened hue woven along the sides thereof, said fabric having also a median line woven therein to indicate where the same may be cut to produce two equal sections, said fabric also having woven therein a central panel of darkened hue extending an equal distance on each side of said median line and providing inner borders for the sections of the fabric when cut along said median line, the borders at the inner and marginal sides of the sections of the fabric when cut being woven to form fold lines whereby the borders may be folded and stitched to form hems of an even width, each border having one face displaying a continuation of a portion of the motif and the other face of the border having the portion between its outer side edge and its fold line marked to blend with the first mentioned face when the hem is formed.

2. A sheet of fabric having a motif therein and bordering panels of a distinctive hue along sides thereof, said fabric having a line therein to serve as a guide when cutting the fabric into sections, the fabric being provided with a panel of a distinctive hue extending equal distances on each side of the cutting line and forming borders for the sections at opposite sides thereof from the first borders when the fabric is cut along the cutting line, each border being provided with a fold line whereby the borders may be folded and stitched to form hems of an even width and each border having one face displaying a continuation of a portion of the motif and the other face of the border having the portion between its outer side edge and its fold line marked to blend with the first face when the hem is formed.

In testimony whereof I affix my signature.

STEPHEN H. BRICE.
